(57) **CLAIM**

The ornamental design for a utility meter interface shroud, as shown and described.

DESCRIPTION

A shroud for encasing a wireless interface to be retrofit in a utility meter.

FIG. 1 is a top perspective view of a utility meter interface shroud according to the present invention;

FIG. 2 is a top view thereof;

FIG. 3 is a front elevation view thereof;

FIG. 4 is a left side elevation view thereof;

FIG. 5 is a right side elevation view thereof;

FIG. 6 is a rear elevation view thereof; and,

FIG. 7 is a bottom view thereof.
